UNITED STATES PATENT OFFICE.

WILLIAM P. KERRIGAN, OF ASTORIA, NEW YORK.

SPARK PLUG.

Application filed July 15, 1922. Serial No. 575,247.

To all whom it may concern:

Be it known that I, WILLIAM P. KERRIGAN, a citizen of the United States of America, residing at Astoria, Queens County, State of New York, have invented certain new and useful Improvements in Spark Plugs, of which the following is a specification.

This invention relates to improvements in spark plugs, which form part of the ignition mechanism of motor vehicles. One of the objects of my invention is to improve spark plugs having in combination with the usual electrodes a spark intensifying device. One of the objections to plugs of this nature is that the starting of a motor by hand cranking is laborious, owing to the fact that the motor has to be spun at a relatively high speed in order that sufficient electric current can be generated to jump both gaps of the plug. The above pertains to motors having magneto ignition. Another objection to these plugs is that they impose additional strain upon spark coils or coil, in a battery ignition device, as current has to be piled up in the condenser before the spark intensifying gap can be jumped, and the greater the gap the more the strain upon the coil, thereby endangering the coil by causing it to become overheated. One of the objects of my invention is to provide means whereby the spark intensifying gap will be bridged until the motor has started, after which the bridging of the gap will be discontinued until the motor is again stopped. When the spark intensifying gap is bridged, the plug will function as an ordinary spark plug. To accomplish the above mentioned result, I employ a thermostatic bridge for the spark intensifying gap, said bridge being operated to break the metallic circuit between the electrodes of the plug by the heat of the plug which will become heated after the motor has been operated a few minutes.

I will now proceed to describe my invention more in detail, the novel features of which I will point out in the appended claims, reference being had to the accompanying drawing, which illustrates a sectional view of a spark-plug of the spark intensifying type having my improvement applied thereto.

The plug herein illustrated is comprised of the separably connected metal body mem-

bers 1 and 2, the member 2 being threaded at 3 to engage threads in an opening in a cylinder-head, a portion of which is indicated by 4. The body member 1 is threaded at 5 to engage threads in a counterbore in the body member 2. The body member 1 carries a casing 6 of insulating material which at its upper end carries an adjustable electrode 7, which is connected by a wire 8 to a distributor (not shown) or in the case of a one cylinder motor to a make-and-break device. A distributor make-and-break device, magneto or spark coil have not been illustrated, for the reason that they are well known, as well as the circuits therefor. The body of the plug carries the usual porcelain insert 8^a which supports an electrode 9 to cooperate with an electrode 10 carried by the body member 2. 11 indicates a glass bushing within the casing 6. The numeral 12 indicates the gap for intensifying the spark at gap 13. The electrode 7 is made adjustable so that gap 12 can be varied to adjust the spark. The electrode 7 is adjusted by screwing same in or out to increase or decrease the gap 12. My improvement comprises a device to bridge the gap 12 so that a metallic circuit between the electrodes 7 and 9 can be established. The bridge member 14 is connected at one end to the electrode 9 (in this instance), in any manner to produce an electrical connection. I have herein illustrated a cap 15 to which the bridge 14 is secured at 16, said cap engaging the threaded end of the electrode 9. The bridge 14 is made up in the form of a thermostat in the usual well known manner by strips of metal having different coefficients of expansion, the detailed structure of the bridge not being illustrated. When the motor is cold, the bridge 14 will, at its free end, rest against electrode 7; hence, there will be a metallic circuit connection between the electrodes 7 and 9, at which time the plug will be similar to the usual spark-plug. When the gap 12 is bridged, in manner described, the spark can be generated by hand cranking. After the motor has been in operation for a while, the plug will become heated, causing the bridge 14 to straighten and break contact with electrode 7, after which the spark gap 12 will function. When the bridge 14 straightens, it will contact with an adjustable threaded stop 17, held in adjusted positions by a nut 18. The gap 19, between electrode 100

110

- 17 and bridge 14, when the contact between said bridge and electrode 7 is broken, will be the maximum gap. Should the electrode 7 be adjusted to produce a gap at 12, too 5 wide for the safety of the coil, the gap 19 will become the spark intensifying gap; hence, gap 19 is a safety gap to prevent the burning out of a coil, should gap 12 be too great. The adjustable stop screw 17 enables 10 one to obtain a desired safety gap 19. When the motor cools off after having been stopped, the bridge 14 will again contact with the electrode 7 to establish a metallic circuit between electrodes 7 and 9.
- 15 What I desire to secure by Letters Patent is:—
1. A spark plug having in combination with its spark gap a supplemental spark intensifying gap, and electrical conducting 20 thermostatically operated means arranged to bridge said gap.
  2. A spark plug having in combination with its spark gap a supplemental spark intensifying gap, and thermostatic means 25 to short circuit the spark intensifying gap.
  3. A spark plug, having in combination with its spark gap a supplemental spark intensifying gap and thermostatic means to control the operation of the spark intensifying gap.
  4. A spark plug, having a plurality of spaced apart electrodes to produce spark gaps, one of said gaps being a spark intensifying gap, conducting means connecting 35 said electrodes across the spark intensifying gap when the plug is cold, and arranged to automatically break said connection when the plug becomes heated.
  5. A spark plug having a plurality of spaced apart fixed electrodes, an adjustable electrode adjacent one of said fixed electrodes also spaced therefrom to provide a spark intensifying gap, and a thermostatic conductor carried by one of the fixed electrodes arranged to bear upon the adjustable electrode 40 contact.
  6. A spark plug having a plurality of spaced apart fixed electrodes, an adjustable electrode adjacent one of said fixed electrodes also spaced therefrom to provide a spark intensifying gap, a thermostatic conductor carried by one of the fixed electrodes arranged to bear upon the adjustable electrode and to break the circuit between the fixed electrode and the adjustable electrode 45 when the plug becomes heated.
  7. A spark plug having a plurality of spaced apart fixed electrodes, an adjustable electrode adjacent one of said fixed electrodes also spaced therefrom to provide a

spark intensifying gap, a thermostatic conductor carried by the fixed electrode arranged to bear upon the adjustable electrode, to break the circuit between the fixed electrode and the adjustable electrode when the plug becomes heated, and means to limit the movement of the thermostatic conductor away from the adjustable electrode to provide a safety spark gap therebetween of predetermined width.

8. A spark plug having a plurality of spaced apart fixed electrodes, an adjustable electrode adjacent one of said fixed electrodes also spaced therefrom to provide a spark intensifying gap, a thermostatic conductor carried by the fixed electrode arranged to bear upon the adjustable electrode, to break the circuit between the fixed electrode and the adjustable electrode when the plug becomes heated, and an adjustable 70 stop to limit the movement of the thermostatic conductor away from the adjustable electrode to provide a safety spark gap.

9. A spark plug having a plurality of spaced apart fixed electrodes, and an adjustable electrode adjacent one of the fixed electrodes and spaced therefrom to provide an intensifying spark gap, means adjacent the adjustable electrode arranged to be spaced therefrom to provide a safety gap, should 85 the gap between the fixed electrode and the adjustable electrode be too great.

10. A spark plug having a plurality of fixed electrodes, an electrode adjustable relative to one of the fixed electrodes to provide 90 a spark gap therebetween, and means adjustable relative to the adjustable electrode to provide a safety spark gap, said means acting as conductor to connect the fixed electrode and the last named adjustable electrode.

11. A spark plug, electrodes spaced apart to provide an intensifying spark gap, means to bridge the gap when the plug is cold and arranged to automatically break 105 contact when the plug becomes heated, and an adjustable stop to limit the movement of the gap bridging device.

12. In a spark plug, a plurality of fixed contacts spaced apart to provide a spark 110 gap, an adjustable electrode adjacent one of the fixed contacts, arranged for movement toward or away from the fixed contact to provide a variable spark intensifying device, and conducting means connected with the fixed contact but spaced from the adjustable contact to provide a safety spark gap.

WILLIAM P. KERRIGAN.
